ATTORNEY

UNITED STATES PATENT OFFICE

ERICH KRAUSE, OF SOUTH JAMAICA, NEW YORK

SAFETY ATTACHMENT FOR GAS VALVES

Application filed April 3, 1928. Serial No. 267,083.

The main object of this invention is to provide an attachment to be used upon gas ranges, ovens, or the like where gas valves are to be manipulated. It is the purpose to provide such a device which will prevent the accidental asphyxiation of persons quartered in rooms when a liquid being heated boils over and extinguishes the flame of the gas burner.

10 Another object of the invention is to provide an attachment used in combination with a range or oven which closes a valve immediately after a liquid which is being boiled by the apparatus extinguishes the flame.

15 The above and other objects will become apparent in the description below in which characters of reference refer to like-named parts in the drawing.

Referring briefly to the drawing:

20 Figure 1, is a longitudinal sectional elevational view thru one corner of a gas range showing the application of the valve closing mechanism.

Figure 2, is a top plan view of Figure 1.

25 Figure 3, is a fragmentary sectional elevational view showing the ball tripping the valve actuating plunger.

Referring in detail to the drawing, the numeral 10 indicates a pipe line which feeds 30 one or a plurality of gas burners 11 which latter are in communication with the pipe line thru branch outlets 12. This pipe line 10, is connected to a source of illuminating gas supply by a nipple 13, along the length 35 of which is mounted a valve body 14, in which is a valve having a square extending shank 15. The square shank 15 has a bell crank mounted thereon. One arm 16 of the bell crank extends upwardly at an angle when 40 the valve is in open position and has a flexible connection 17 secured thereto. The opposite arm 18 of the bell crank has a finger ring 19 formed at its extremity. Beneath the burner members 11 and the pipe line 10, a 45 declining platform 20, is mounted between the walls 21, of the gas range, one of said walls being shown in Figure 1. This platform has an opening 22 therein toward which the surfaces of the platform decline so that 50 any liquids falling on said platform will

trickle down and pass thru the opening. Adjacent to opening 22 the upper end of a cylinder 23 is mounted. This cylinder hangs suspended from the lower surface of the platform 20 to which it is attached and uses a 55 longitudinal plunger 24. The upper end of this plunger has an extension thereon to which is secured the lower suspended end of the flexible connection 17. A coil spring 25 seats on the upper face of the plunger and is 60 positioned between same and the platform 20, and is adapted to be in compressed condition when said plunger assumes its uppermost position, as indicated in Figure 1. The wall of the cylinder 23, has a longitudinal slot 26 65 therein in which a relatively small lever 27 is movable. This lever is fulcrumed intermediate its length and its upper end is adapted to jut into the confines of the cylinder so that the lower face of the plunger 24 70 may seat thereon. The lower end of the lever 27 is formed into an outwardly curved projection 28 and is adapted to project into a chute 29 at an enlarged portion. This chute extends vertically upward and at its 75 upper end a declining S-curved run-way 30 is formed.

Beneath the platform 20 is member 31, which forms a floor for the valve actuated mechanism. This floor supports a triangular 80 block 32, whose apex is located at its extreme upper end. A bar 33 is balanced upon the block 32 and is retained in located position by forming a notch 34 in the bar. At one end the bar has a threaded extension 35 formed 85 unitary with the bar, which has engaged thereon an adjustable weight 36 which is adapted to compensate for the variability of weight of a ball 37. The ball of relatively heavy material, is seated in a cup-shape recess 38 which is formed at the opposite end of the bar 33. Intermediate the length of the bar between the block 32 and the cup-recess of the bar a stud 39 projects vertically 90 upward and is surmounted by a hemi-spherical container 40 which is always within range 95 of having the drippings of liquid trickle thru the opening 22 and fall therein.

I claim:

1. A device for closing a valve comprising 100

a lever secured to a valve, a weight suspended from said lever, said weight adapted to drop and rotate said lever to close said valve, means for latching said weight in raised position to retain said valve lever in open position, a platform above said weight, an opening in said platform adapted to drain boiled over liquid, a ball, and normally balanced means supporting said ball, said ball being adapted to trip said latching means and release said weight when said balanced means is over-balanced.

2. A device for closing a valve comprising a lever secured to a valve, a weight suspended from said lever, a latching lever pivoted beneath said weight, a projection on said lever, said lever engaging said weight to retain the latter in raised position, a platform, a normally balanced bar beneath said platform, and means adapted to roll from said balanced bar and trip said latching lever when said bar is over-balanced.

3. A device for closing a valve comprising a lever secured to a valve, a weight suspended from said lever, a lever pivoted beneath said weight, a projection on said lever, said lever engaging said weight to retain the latter in raised position, a platform, a normally balanced bar beneath said platform, a weighted ball normally seated on one end of said bar when the latter is in balanced position, a runway beneath said bar, said bar when over-balanced being adapted to unseat said weighted ball to cause the latter to fall upon said runway and trip the last-named lever to release said lever from engagement with said weight, and means for accumulating the drippings from said platform to over-balance said bar, a container mounted on said bar, said container being immediately below the opening in said platform, said container when receiving drippings from said opening being adapted to over-balance said bar and unseat said weighted ball to trip and release said weight suspended from said first-named lever.

In testimony whereof I affix my signature.
ERICH KRAUSE.
